UNITED STATES PATENT OFFICE.

ADOLPH F. POZDECK, OF NEWARK, NEW JERSEY.

MANICURING INSTRUMENT.

Application filed October 29, 1921. Serial No. 511,261.

To all whom it may concern:

Be it known that I, ADOLPH F. POZDECK, a citizen of Czecho-Slovakia, and residing at Newark, in the county of Essex and State 5 of New Jersey, have invented a certain new and useful Improvement in Manicuring Instruments, of which the following is a specification.

My invention has for its object to provide a device in which two of the most important tools for manicuring will be combined in a single instrument. It is well known that it is a fruitful source of annoyance to have a number of tools to take care 10 of while doing work of this character, and therefore anything that will lessen the number which is required to be used by the manicurist, will be desirable.

Another feature of my invention is to provide a file which will be formed upon a concave surface, thus avoiding the necessity for 15 flexibility in the file and yet producing highly satisfactory results.

My means of accomplishing the foregoing 20 objects may be more readily understood by having reference to the accompanying drawing which is hereto annexed, and is a part of this specification, in which:

Fig. 1 is a side elevation of my improved 25 device.

Fig. 2 is a sectional view taken on the line 2—2 in Fig. 1.

Fig. 3 is a detail view.

Fig. 4 is a fragmentary detail view of 30 the end of one of the handles.

Similar reference numerals refer to similar parts throughout the entire description.

As shown in the drawing, the instrument comprises two cutting blades 1 and 2, which

are hinged together by a pivot pin 3, and are 40 provided with handles 4 and 5. These handles are curved so that the inner edges 6 and 7 are concave. Upon this concave surface, serrations are cut to form files. The one on the surface 6 may be of a different degree 45 of fineness than that upon the surface 7, thereby providing one file for cutting, and a second file, which should be fine enough to take the place of the emery board commonly employed for this purpose, while the 50 clippers, preferably of the type illustrated, are especially desirable for use in connection with manicuring. One end 8, of one of the handles is pointed and acts as a nail cleaner.

It will be obvious to persons skilled in the art that the device as hereinbefore described forms an exceedingly desirable tool, and one of great convenience since it furnishes the three different devices in a single instrument.

Having described my invention what I regard as new and desire to secure by Letters Patent is—

1. In a device of the character described, 65 a pair of nail clippers, the handles of which are curved, a plurality of serrations cut upon the concave surface of the handles for the purpose set forth.

2. In a device of the character described, 70 a pair of nail clippers, the handles of which are bowed outwardly, serrations cut upon the inner concave surfaces of the handle, the serrations on one handle being finer than those of the other, for the purpose set forth. 75

In testimony whereof I have signed the foregoing specification.

ADOLPH F. POZDECK.
